UNITED STATES PATENT OFFICE.

MADISON L. SHORE, OF RALEIGH, NORTH CAROLINA.

SHIPPING-CRATE FASTENER.

1,253,637.

Specification of Letters Patent. Patented Jan. 15, 1918.

Application filed November 9, 1915. Serial No. 60,566.

To all whom it may concern:

Be it known that I, MADISON L. SHORE, a citizen of the United States, residing at Raleigh, in the county of Wake and State of North Carolina, have invented new and useful Improvements in Shipping-Crate Fasteners, of which the following is a specification.

This invention relates to improvements in shipping cases or boxes of that type primarily adapted for the transportation of bottles in a filled or emptied condition.

A further object of the invention is the provision of a device of the above-stated character wherein an improved fastening means is employed for securing the cover to the box in such a manner as to prevent any accidental displacement or loosening of the fastener during storing or transportation of such cases.

A still further object of the invention is the provision of a cover having cut out portions adapted to receive portions of the locking strip therein, whereby the means for fastening the cover to the shipping case will at all times lie below the plane of the top.

With the above and other objects in view, the invention consists in the novel features, details of construction and combination of parts which will hereinafter be more fully set forth, illustrated in the accompanying drawings and pointed out in the appended claims.

In the accompanying drawings:

Figure 1 is a detail perspective view of a shipping case with the closure secured thereto.

Fig. 2 is a top plan view of the shipping case with the cover removed therefrom.

Fig. 3 is a detail perspective of the cover removed from the box.

Fig. 4 is an end view of the cover.

Fig. 5 is a detail section showing the manner of securing the fastening studs to the shipping case.

Fig. 6 is a detail perspective view of a tool used in opening or closing the box.

Referring more particularly to the drawings, 5 denotes a shipping case of substantially rectangular configuration, and may be made of any suitable material, but for the purpose of illustration, the same is shown as being constructed of wood. The upper transverse edges of the end walls 6 of the case are formed with a pair of spaced

notches 7, the pairs of notches of each end wall of the case aline longitudinally with each other and the function of such notches will be clearly set forth as the description of the invention is proceeded with. A cover 8 is provided for closing the shipping case 5. In order to secure the cover 8 to the case without the employment of nails, screws, or the like, whereby avoiding the splitting or marring of either the cover or goods, and further to permit of the case being further utilized to return the empty bottles or the like containing the goods shipped therein, I provide an improved fastening device 9 for fastening the cover to said box. The fastening device in this particular instance embodies a pair of substantially U-shaped metallic clips 10 having spaced parallel limb portions 11 and a connecting portion 12. The clips 10 straddle the upper ends of the end walls 6 of the case and position the connecting portions 12 thereof within the notches 7, the connecting portions being disposed flush with the uppermost edges of the end walls 6. The limb portions 11 of the clips 10 are apertured as at 13 for permitting a removable fastening device to pass therethrough and through the outer and inner faces of the end walls 6 of the case for attaching the clips thereto. An upstanding threaded stud 14 is fixedly secured to the connecting portion 12 of the clips by the welding of the same or the like thereto.

The cover 8 is cut out along its opposite transverse ends to provide a pair of spaced longitudinally alined cut out portions 15. A metallic strip 16 is fastened along the opposite upper transverse ends of the cover 8 and bent around the opposite side edges thereof as at 17 and thence bent inwardly 95 and at right angles to the portion 17 and apertured as at 18 for receiving a fastening device 19 for permanently fastening each of the strips to the under side of the cover. The portions 17 of the strips are seated 100 within notched out portions 20 for positioning the strip flush with the opposite longitudinal side edges of the cover. The said metallic strips 16 are stamped downwardly as at 21 at spaced intervals throughout its 105 length to provide a pair of substantially U-shaped resilient keepers 22, the said keepers 22 are disposed within the cut out portions 15 of the cover and have their limb portions 23 in contact with the opposed faces

of the cut out portions. The connecting portion of the U-shaped keepers is apertured as at 24 to permit the passage of the stud 14 therethrough when the cover is in applied position. In order to lock the cover securely to the shipping case and to prevent any accidental loss thereof, I provide locking nuts 25 which when in a tightened position are disposed wholly below the plane of the cover and thereby prevent any accidental tampering or striking of the nuts during the storage or shipment of the cases.

From the foregoing description, it will be apparent that after the receptacles containing the goods to be shipped have been packed in the shipping cases, the cover may be readily applied to the box in the manner above described and thereby prevent the use of the ordinary fastening means such as screws, 20 nails, or the like, and thereby prevent the splitting or marring of the case or cover to such an extent as to prevent any further use of the case. With my improved fastening means, however, it is my object, that after 25 the vessels, which may be bottles or the like have been emptied, such vessels may be returned in the same box in which they were received.

The numeral 26 designates a preferred 30 form of wrench having a socket 27 adapted to fit the locking nuts 25 to permit of a convenient opening or closing of the box as the occasion may demand. It is my object to conveniently attach this tool to a shipment of crates or an individual tool may be furnished to customers receiving such goods.

From the foregoing description, taken in connection with the accompanying drawings, the advantages of construction and of the 40 method of operation will be readily apparent to those skilled in the art to which the invention relates, and while I have described the principles of operation of the device together with the device which I now consider to be the best embodiment thereof, I 45 desire to have it understood that the device shown is merely illustrative and that such changes may be made when desired as are within the scope of the claims appended 50 hereto.

Copies of this patent may be obtained for five cents each, by addressing the "Commissioner of Patents, Washington, D. C."

Having described the invention, what is claimed is:

1. A shipping crate embodying end walls, a cover therefor having spaced notches, a series of studs secured upon the upper edges 55 of the end walls of the crate, a locking strip connected along the opposite transverse ends of the cover and struck downwardly at portions intermediate its length to provide spaced apertured keepers having their limbs 60 contacting with the opposite walls of the notches formed in said cover, the said studs of the crate projecting through the apertures of the keepers, and nuts threaded on said studs for causing the locking action of the 65 cover to said crate.

2. A shipping crate comprising end walls, a cover therefor, a fastening device for securing a closure to a crate embodying a series of threaded studs secured to the crate, 70 a locking strip connected with the opposite transverse ends of the cover and struck downwardly at portions intermediate its length to provide spaced resilient apertured U-shaped keepers, the studs projecting 75 through the apertures of said keepers, and nuts threadedly mounted on the studs for locking the closure to the crate.

3. In a device of the class described, a receptacle, a closure therefor having its opposite transverse ends formed with spaced cut-out portions, a locking strip connected to the opposite transverse ends of the cover and provided throughout its length with downwardly bent resilient U-shaped keepers, 85 the said keepers fitting within the cut-out portions of the cover, a series of studs carried by the receptacle and projecting through the keepers, and means threadedly mounted on the studs and seated within the said keepers for detachably connecting the closure upon said crate.

In testimony whereof I affix my signature in presence of witnesses.

MADISON L. SHORE.
